Primary Examiner — Rashida Johnson(74) *Attorney, Agent, or Firm* — Intellalegal; James W. Pravel(57) **CLAIM**

The ornamental design for a trombone grip, as shown and described.

DESCRIPTION

FIG. 1 is a left side perspective view of a trombone grip showing my new design;

FIG. 2 is a front elevation view thereof;

FIG. 3 is a rear elevation view thereof;

FIG. 4 is a right side elevation view thereof;

FIG. 5 is a top plan view thereof;

FIG. 6 is a bottom plan view thereof;

FIG. 7 is a right side elevation view thereof, showing the new design on a trombone; and,

FIG. 8 is a reduced perspective view, showing the design in use on a trombone.

The broken lines are for illustrative purposes in showing the trombone grip in use and form no part of the claimed design.

1 Claim, 6 Drawing Sheets(56)
